(57) **CLAIM**

The ornamental design for a pet toy, as shown and described.

DESCRIPTION

FIG. 1 is a front top perspective view of a pet toy showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating elements of the pet toy that form no part of the claimed design.

1 Claim, 6 Drawing Sheets
